UNITED STATES PATENT OFFICE

AUGUST HELLERMANN, OF FREIBURG, GERMANY, ASSIGNOR TO THE FIRM GESELLSCHAFT FÜR WIRTSCHAFTLICHEN BAHNOBERBAU M. B. H., OF FREIBURG, GERMANY

RAILWAY RAIL JOINT

Application filed September 12, 1930, Serial No. 481,554, and in Germany September 22, 1926.

This invention relates to railway or tramway rail joints in which an auxiliary rail is disposed at one side of the abutting ends of the rails.

There are already known butt joints for railway rails in which the auxiliary rail is rigid and in certain cases is elevated above the tread face of the rails so as to prevent the descent of the vehicle wheel in passing over the gap at the joint, or, rather, to a certain extent to lift the wheel over the gap. It has also been proposed as disclosed in my Swiss Patent 132,837 granted July 16, 1929 to make the auxiliary rail resiliently yielding in the direction of the wheel pressure in order to take-up elastically the shocks resulting from passage of the wheel over the gap. In order that this action of the resilient auxiliary rail may be ensured with wheel loads likely to be met with in practice the tread surface of this resilient auxiliary rail was elevated somewhat above the tread surface of the rails alongside the gap, the length of the elevated portion of the auxiliary rail being only slightly greater than the width of the gap. Extensive tests have been made on German railroads with the joint construction above described and which is illustrated in my Swiss patent above stated and it was discovered that it is necessary that the resilient auxiliary rail must have such strength of resiliency that it is retained elevated beyond the surface of the tread wheels under the maximum permissible load. Only if this condition is preserved, the object of the invention can be achieved. Only in this case are the wheels prevented from dropping while passing over the butt joint and when the auxiliary rail has its upper surface above the tread surface of the main rails on a maximum permissible load, only then are the wheels prevented from dropping while passing over the butt joint and only then it is that within the region of the butt joint, the car wheels are exclusively carried by the auxiliary

The known constructions of butt joints for railway rails have not been extensively adopted in practice because they have only to a small extent answered expectations. The reason for this is that in the construction and arrangement of such auxiliary rails assumptions have been made which are not in correspondence with actual conditions in the passage of the wheels over the joints. It has only recently been ascertained, as a result of extensive experimental research, that the production of shocks on passage over the joint is less due to the interruption of the track by the gap, than to the alteration of the static conditions at the joint relatively to the interrupted rail and to the alteration of the curve or deflection wave travelling with the wheel. The formation of this curve in the region of the joint depends essentially on the nature of the joint and the mounting of the rail ends. In every case by the alteration of the curve in the region of the joint there is brought about sudden alteration in the direction of movement of the wheel. For example, in the case where the rail ends are mounted on the same double sleeper or rail-tie which is less yielding than the other sleepers or ties there results reduction of the pitch of the curve in front of the gap and elevation of the track, while behind the gap the track again falls to the normal level. The consequence is that in front of the gap the vehicle is accelerated in upward direction with substantial stress on the rail and in consequence of its inertia rises from the tread face of the rail so that it jumps on to the next rail, beyond the gap causing a considerable shock. In the case where the rail ends are mounted freely as beams on two sleepers arranged at a certain distance apart there is effected in front of the gap under the load of the wheel increase of the pitch of the curve, that is lowering of the track. In consequence, the wheel jumps with considerable shock on to the rail end beyond the gap and must be accelerated in upward

direction up to the level of the track, thus stressing severely this rail end. The length of the section of the tread surface which departs from the normal rectilinear track in consequence of the alteration of the curve or deflection wave depends on the mode of mounting the rail ends and is the same for all wheel loads. With the load there is altered only the extent to which the tread surface of the rail departs from the normal rectilinear track. The length of this section can be ascertained practically in a very simple manner by test for every style of bedding the rails.

The invention is based on the recognition of the circumstance that in the region of the gap increased stressing of the rail ends can only be avoided by maintaining the resilient auxiliary rail over the entire region of the section of the tread surface that departs from the normal rectilinear track in supporting contact with the wheel. For this purpose, according to the invention, the construction and arrangement of the resilient auxiliary rail, which in known manner is elevated in unloaded condition beyond the tread surface of the rails, are such that the auxiliary rail even under the maximum permissible load remains elevated above the tread surface of the rails in the region of this section. It has been found that this condition is fulfilled when the elevated portion of the tread surface extends, in the case where the rail ends are mounted, on a double sleeper, up to about midway between said sleeper and the two adjoining sleepers, and, in the case where the rail ends are mounted on two sleepers, for about the length of the distance between these two sleepers.

In either case not only the gap but also the entire section of the tread face of the rails which departs from the rectilinear track is bridged by the auxiliary rail. In the case where the rail ends are mounted on two sleepers alteration of the direction of movement of the wheels can be almost entirely avoided, while in the case where the rail ends are mounted on the same double sleeper the alteration of direction can be made so gradual that the stresses on the auxiliary rail due to the inertia of the wheel are very slight and lifting of the wheel from the auxiliary rail is avoided. Wear in the neighbourhood of the gap can only take place on the auxiliary rail which can be renewed if required with slight expenditure of time and money.

Two embodiments of the invention are illustrated diagrammatically in the accompanying drawings.

Fig. 1 shows in side elevation a butt joint for railway rails in which the rail ends are mounted freely as beams on two sleepers.

Fig. 2 shows also in side elevation a butt joint for railway rails in which the rail ends are mounted on the same double sleeper.

Fig. 3 is a section on the line 3-3 of Fig. 1 or Fig. 2.

With respect to both embodiments it is assumed that the vehicle wheel *a* represented by a chain-dotted circle moves in the direction 70 of the arrow *x*, that is, from left to right. The rail end in front of the gap *b* is denoted *c'* and the rail end in the rear of the gap *b* is denoted *c*². Under the load of the vehicle *a* the rail suffers deflection in consequence of the 75 yielding nature of the bed so that the tread surface beneath the wheel *a* assumes the form of a curve which is referred to as the deflection curve or wave. On the assumption that the yieldability of the bed and the stiffness 80 of the rail are uniform over the entire length of the rail, the deflection curve which travels with the wheel *a* has always the same form so that the lowest point *e* of the wheel *a* describes a rectilinear path. As, however, in 85 the vicinity of the gap at the joint both the stiffness of the rail or bending resistance and also the yieldability of the bed are altered, the form of the said curve must alter so that the path *f* of the point *e* assumes over a section *g* a form departing from a straight line. In the embodiment shown in Fig. 1, at this section *g* there would be first a deviation downwards and then a deviation upwards of the line *f* which represents the track of the 90 wheel; while in the embodiment according to Fig. 2, in consequence of the resistance offered by the double sleeper *h* carrying both the rail ends, the line *f* deviates upwards in front of the gap *b* and deviates downwards to the normal level behind the gap.

Alongside the rail ends the resilient auxiliary rail *i* is mounted on blocks *k* and *l*. The two ends of this resilient auxiliary rail are overturned or looped and engage the 105 blocks *k* and *l* in such wise that the portion in front of the gap *b* is immovable in both directions, while the end behind the gap can move in the direction of travel. This is secured by forming the loop engaging the block 110 *k* with an upwardly directed lug *i'*, causing the loop to engage the block and thus prevent longitudinal movement of this end of the auxiliary rail. The auxiliary rail has such strength of tension or such resistance to 115 depression that the tread face of this auxiliary rail at all times, and under all permissible loads is elevated above the tread face of the main rails for the length of the section *g* to such an extent that it retains an elevated 120 position above the tread faces of the main rails in the region of this section *g* even under the maximum permissible load. In the embodiment shown in Fig. 1 the elevated portion of the auxiliary rail extends for about 125 the length of the distance between the two sleepers *m* and *n*, while in the embodiment shown in Fig. 2 the elevated portion of the auxiliary rail extends about midway between the double sleeper *h* and the two adjoining 130

sleepers *o* and *p*. The result is obtained that in the region of the section *g* at which the tread surface departs from the rectilinear track in consequence of the alteration 5 of the deflection curve the vehicle wheel is carried by the auxiliary rail *i*, so that in a sense the section *g* is bridged over it being understood that the weight of the rolling stock 10 causes a depression of the rail *i* nearly to the level of the upper surfaces of the main rails.

I claim:

1. In a railway track structure, two abutting rails and an auxiliary rail disposed at one side of and closely adjacent the abutting 15 rail ends, the auxiliary rail having its upper surface upwardly curved and the middle portion of said surface extending above the tread faces of the abutting rail ends, the auxiliary rail being resiliently depressible under load 20 but being of such resilient strength that the middle portion of the auxiliary rail remains elevated above the surfaces of the abutting rails under maximum permissible load of rolling stock.

2. In a railway track structure, two abutting rails and an auxiliary rail disposed at one side and closely adjacent the abutting rail ends, the auxiliary rail being resilient and gradually increasing in thickness from 25 its ends towards its middle, and the upper surface of the auxiliary rail being upwardly curved, the middle portion of said upper surface extending above the tread surfaces of the abutting rail ends, the auxiliary rail being 30 depressible under load against its resilience, but the resilience of the auxiliary rail being such that the middle portion of the auxiliary rail remains elevated above the surface of the abutting rails under maximum 35 permissible load of rolling stock.

3. In a railway track structure, two abutting rails, sleepers disposed in spaced relation to the abutting ends of the rails, an auxiliary rail disposed at one side and closely 45 adjacent the abutting rail ends, the auxiliary rail having its upper surface upwardly curved and the middle portion of said surface extending above the tread faces of the abutting rail ends, the elevated portion of the 50 tread surface of the auxiliary rail being of a length approximately equal to the distance between said sleepers, the auxiliary rail being resilient and depressible under load but offering such resistance to depression 55 that the middle portion of the auxiliary rail remains above the surface of the abutting rails under maximum permissible load of rolling stock.

4. In a railway track structure, two abutting rails, a sleeper disposed beneath the abutting ends of the rails, sleepers disposed one on each side of the first named sleeper, an auxiliary rail disposed at one side and closely adjacent the abutting rail ends, the 60 auxiliary rail having its upper surface up-

wardly curved, the elevated portion of the tread surface of the auxiliary rail extending to a point midway between the sleeper supporting the abutting ends of the rails and the two adjoining sleepers, the auxiliary rail 70 being resiliently depressible under load but being of such strength that the middle portion of the auxiliary rail remains elevated above the surface of the abutting rails under maximum permissible load of rolling stock. 75

In testimony whereof I hereunto affix my signature.

AUGUST HELLERMANN.
